H. W. DENHARD.

ELECTRIC HEATER.

APPLICATION FILED JULY 17, 1908.

1,121,074.

Patented Dec. 15, 1914.

UNITED STATES PATENT OFFICE.

HARRY W. DENHARD, OF SAN FRANCISCO, CALIFORNIA, ASSIGNOR, BY MESNE ASSIGNMENTS, TO THE CUTLER-HAMMER MFG. CO., A CORPORATION OF WISCONSIN.

ELECTRIC HEATER.

1,121,074.

Specification of Letters Patent.

Patented Dec. 15, 1914.

Application filed July 17, 1908. Serial No. 444,059.

To all whom it may concern:

Be it known that I, HARRY W. DENHARD, a citizen of the United States, residing at San Francisco, in the county of San Francisco, State of California, have invented certain new and useful Improvements in Electric Heaters of which the following is a specification.

My invention is a modification of the form of electrical water heater shown in an application filed by me on the 24th of June 1908, serially numbered 440371. In this application I have shown a closed chamber containing a series of electrodes with spaces between them and out of electrical connection normally, the connection between the positive and negative electrodes being made by filling the spaces between the electrodes with liquid as by the filling of the chamber.

The present invention is a modification of the device of the application and comprises an open bath with a series of electrodes arranged therein in sets, the sets being insulated from each other but being so arranged within the bath or receptacle as to be surrounded by the water or other liquid filling the same and offering a resistance between the positive and negative electrodes so as to cause a heating action as the current passes from one electrode to the other through the liquid. Instead of the closed chamber, as in the application referred to, I adapt the invention to any form of open receptacle, and this may be made in a variety of shapes, and used for many purposes.

In the drawing, Figure 1 is a sectional view of a receptacle made in accordance with this invention; Fig. 2 is a plan view; Fig. 3 is a horizontal section through the electrodes.

In the figures 1 represents a receptacle made of porcelain or other non-corrosive material, which may be of any shape or size according to the purpose to which it is adapted. It may be ornamented in any suitable or desirable manner in case it is intended for use on the table in the heating of liquids in the preparation of food. Extending across from one wall to another are a series of electrodes which may be in two sets of three each as shown, or in any suitable number according to the particular requirements. These electrodes are alter-

nately arranged, A, B, C, being positive and D, E and F negative electrodes. The electrical connections are shown at 15. The electrodes of the positive series are supported at the left hand side by rubber gaskets S, and at the right hand side in recesses in the walls of the porcelain receptacle, while the electrodes of the negative set are reversely arranged. Thus there is no direct electrical connection between the electrodes, and there can be no passage of the current until the electrodes are submerged and the spaces between are filled with water or other liquid. In the passage of the current through the resistance offered by the water heat is generated and the liquid contained within the receptacle heated very rapidly. When there is no liquid within the receptacle there is of course no action and no burning out of the parts.

What I claim is:

1. In an electric heater, the combination of a receptacle having vertical walls, electrodes submerged within a liquid therein and passing through said vertical walls, means for maintaining a water tight joint between said electrodes and said walls and electrical connections for said electrodes external to said receptacle.

2. In an electric heater, the combination of a receptacle for liquid, electrodes immersed in said liquid and spanning said receptacle and extending through the vertical walls thereof, means for maintaining a water tight joint about each electrode and electrical connections for said electrodes at the protruding ends of the same.

3. An electric heater comprising a receptacle having openings in its walls on opposite sides and recesses opposite each opening, gaskets in each opening, electrodes each having one end passing through the openings and the other seated in the opposite recess and electrical connections for said electrodes.

4. An electric heater comprising an open receptacle having openings in its walls in opposite sides and recesses opposite each opening, rubber gaskets in each opening, and electrodes each having one end passing through the gaskets and its other end seated in the opposite recesses.

5. An electric heater comprising a receptacle, positive and negative electrodes ex-

bending across the same and having both ends supported in the walls thereof, the ends of the positive electrodes extending through the walls on one side and the ends of the negative electrodes extending through the wall on the other side and electrical connections for said electrodes.

6. An electric heater comprising a receptacle having openings in its walls and recesses, in its opposite walls in alignment with said openings and a plurality of alternately arranged positive and negative electrodes extending through said openings and into the recesses, said positive and negative electrodes extending into said receptacle from opposite sides thereof.

7. In an electric heater, the combination of an open receptacle having a flange around its periphery, electrodes extending through the walls of said receptacle, and means located beneath said flange for maintaining a water tight joint about said electrodes.

8. In an electric heater, the combination of a receptacle having a transversely extending flange on its periphery, electrodes extending through the walls of said receptacle, means surrounding the ends of said electrodes and located beneath said flange for maintaining a water tight joint between the electrodes and the walls of the recep-

tacle, and electrical connections for said electrodes.

9. In a device of the class described, a liquid receptacle, electrodes each supported at opposite ends in the walls thereof, said electrodes being spaced apart and arranged parallel in substantially the form of a grid, whereby free circulation of said liquid is permitted, said grid being arranged in a horizontal plane to insure immersion of the entire grid in a given depth of liquid.

10. In a device of the class described, a shallow, open liquid receptacle of insulating material, electrodes in the form of conducting rods each supported at opposite ends in the walls thereof, whereby they are insulated from each other, said electrodes being spaced apart, arranged horizontally and parallel to each other in the form of a grid, one end of each electrode protruding through its supporting wall to provide a terminal connection outside of said receptacle.

In testimony whereof I have affixed my signature in the presence of two witnesses this 15th day of June, 1908.

HARRY W. DENHARD.

Witnesses:

FRANK L. OWEN,
A. DIXON.
